(57) **CLAIM**

The ornamental design for a display screen with graphical user interface, as shown and described.

DESCRIPTION

FIG. 1 is a front view of a display screen with graphical user interface showing my design according to a first embodiment; and,

FIG. 2 is a front view of a display screen with graphical user interface showing my design according to a second embodiment.

The broken lines show portions of the graphical user interface and form no part of the claimed design. The outermost solid-line rectangle illustrates the perimeter of the display screen.
